UNITED STATES PATENT OFFICE.

PHILIP M. RIMMER, OF DETROIT, MICHIGAN.

VAPORIZER AND CARBURETER.

1,106,935.

Specification of Letters Patent. Patented Aug. 11, 1914.

Application filed September 17, 1913. Serial No. 780,188.

To all whom it may concern:

Be it known that L. PINEYER M. RIMMER, a citizen of the United States, residing at Detroit, in the county of Wayne and State of Michigan, have invented a certain new and useful Improvement in Vaporizers and Carbureters, of which the following is a full, clear, and exact description.

This invention relates to carbureters, the object being to provide a carbureter in which the liquid fuel is vaporized in the carbureter and before the air is mixed therewith.

The invention further resides in the construction of the carbureter, whereby the quantity of vaporized fuel is governed in accordance with the quantity of air, and further the quantity of vaporized fuel and gas is controlled by the throttle.

Generally speaking, the invention comprises the elements and combination thereof set forth in the accompanying claims.

Reference should be had to the accompanying drawings forming a part of this specification, in which—

Figure 1 is a sectional elevation through the carbureter. Fig. 2 is a sectional elevation of a modified form of top portion for the carbureter. Fig. 3 is a top plan view with parts in section. Fig. 4 is an end elevation looking toward the air intake pipe. Fig. 5 is a sectional elevation of a modified form of device. Fig. 6 is an elevation with parts in section of a still further modification of the device.

The carbureter comprises a float chamber which is within a casing 1. This casing is provided with a cover 2 which is secured in place in any desired manner. The cover 40 and the bottom of the casing support a rod 3 upon which there slides a float 4, the float and the rod 3 being of usual construction.

Communicating with the chamber within the casing 1 is an inlet conduit 5. This conduit extends within the casing 1. A valve 6, which is of conical shape, cooperates with the top opening of the conduit 5 and by its movement in and out of the said conduit controls the quantity of fuel which is passing through the conduit 5. This valve is provided with an extension 7 which moves within a housing 8 carried upon the cover 2.

A lever 9 is pivoted upon the under side of the cover 2 in any desired manner, and one end bears upon the valve 6, and at the other

end bears upon the float 4. The valve 6 and its cooperative action with respect to the float 4 will be well understood, as this construction in its function is old in the art.

Adjacent the chamber formed in the casing 1 is a vaporizing chamber formed within a casing 10. This casing is preferably made integral with the casing 1, and the bottom of the casing 10 is provided with a series of ribs or ridges 11. The casing 10 is formed with extending flanges 12 beneath the bottom 11 which forms an opening adapted to receive a heating element 13. The opening for the heating element is closed by means of a cover 14 which may be retained upon the casing in any desired manner. This cover is provided with a suitable opening and hollow nipple indicated at 15, through which the electrical conductors for the heating element 13 may be introduced. The chambered portions within the casings 1 and 10 communicate with each other by means of a passage 16. It will therefore be apparent that the fluid fuel which is supplied to the float chamber will rise to the same level within the vaporizing chamber, and I arrange the float so that the level of the fuel within the float chamber and the vaporizing chamber is such that the fluid fuel just covers the ribs 11.

In a portion of the wall of the casing 10 there is formed a conduit 17, which at its lower end is enlarged and formed as a seat to cooperate with a ball valve 18. This ball valve is spring pressed by a spring 19 and the spring is held by means of a nut 20 which is threaded within a suitable opening in the wall. The enlarged portion within which the ball valve 18 is seated communicates with a cross passage 21 which also communicates with a conduit 5 by which fluid fuel is supplied to the float chamber.

In the operation of the carbureter it will be apparent that the heat supplied by the heating element 13 will vaporize the fluid fuel which may be in contact with the ribs 11. If, perchance, the exit from the vaporizing chamber is closed, considerable pressure will be developed within the vaporizing chamber, which, pressing upon the top surface of the fuel passing through the passage-way 16, will cause the float to rise and so close the valve 6, thus preventing any further feed through the conduit 5 to the float chamber. As this pressure increases, it must

find an outlet, and this is provided by way of the passageway 17. When the vapor pressure within the vaporizing chamber rises sufficiently high, it will exert sufficient pressure upon the ball valve 18 to unseat the same, and thus vent the vaporized gas so that it may pass through the passageway 21 into the conduit 5, where meeting with the comparatively cool fluid fuel, it will be condensed. It will thus be seen that I have provided a carburetor which is proof against destruction, even if inadvertently the heating element be allowed to remain in action.

At the upper end of the chamber 10 there is a casing 22 which is provided with a longitudinal opening adapted to receive a valve 23, and the casing is also provided with a transverse opening 24, which opening is controlled by the valve 23. This valve 23 at a portion thereof is cut away, as indicated at 25, so that as this portion 25 is moved into registry with the opening 24, it will permit the passage of the vaporized fuel through the opening 24. The portion 25 is provided with slanting walls, as is clearly indicated in the drawing, so that the passage of the vaporized gas is gradually increased as the valve 23 is moved into registry with the opening 24.

Above the casing 22 is a casing 26 which is provided with the usual throttle valve 27, and with an extending portion 28 which incases a valve 29, the same being to govern the admission of air through the opening end of the extension 28 of the casing 26. The valve 29 is mounted upon a transverse stem 30, to which is secured upon the outer side thereof a lever 31, and this lever at its lower end extends within a slot formed in the valve 23, as indicated at 32 in Fig. 1.

The throttle valve 27 is mounted upon a transverse pin 33, and the extension of this pin upon the outside of the casing is secured to a lever 34, which, in turn, is secured to a lever 35 that also is pivoted at its opposite end to the lever 31. It will therefore appear from the drawing and the description, that the throttle valve 27, the air valve 29 and the valve 23 are all interlinked so that the ordinary mechanism carried by an automobile by which the throttle valve is controlled will also serve to control the admission of air and the admission of vaporized fuel to the engine.

In Fig. 2 I have shown a modified condition in which the casing 36 houses a transverse valve 37, which is the same in construction and function as the previously described valve 23. This casing 36 is provided with a transversely extended opening or port 38 which communicates with the chamber within a casing 39 which is provided with an extension 40, which extension is open to the air. This extension 40 of the casing 39 houses an air valve 41. This

valve 41 is operated by an external lever 42, and the lower end of the lever extends within a slot 43 formed in the valve 37.

The construction shown in Fig. 2 shows a construction wherein the air admission valve and the valve controlling the port between the air chamber and vaporizing chamber are simultaneously controlled, while if a throttle valve is used, it will be independently operated. In this respect it differs from the showing in Fig. 1.

In Fig. 5 I have shown an arrangement whereby the valve governing the port from the vaporization chamber is operatively secured to the throttle valve so as to operate in fixed relation thereto. The admission of air is controlled by an automatic valve which comprises a valve rod 45 which is secured in a part of the casing. Upon the rod is a valve disk 46 carried by a sleeve 47. The sleeve is engaged by a coiled spring 48 which at its opposite end engages a nut carried by the rod. The valve disk 46 cooperates with an opening 44 in the casing through which air may pass as the valve disk 46 is lifted. This valve will automatically admit air as it is lifted against the action of spring 48 due to the suction produced by the engine to which the carburetor is attached.

In Fig. 6 there is shown a modification of the arrangement of valves and their operating means. This modification consists in placing in connection with the air valve 29 an auxiliary air valve 50, which valve is of the same construction as shown for the automatic valve in Fig. 5, and needs no further description. It will thus be seen that in addition to the manually controlled air valve the automatic valve will admit extra amounts of air when necessary.

Having described my invention, what I claim is:

1. In a vaporizer and carburetor, the combination with a float chamber and a vaporizing chamber, said chambers communicating with each other, a heating element associated with the vaporizing chamber, means controlling the exit of the vaporized fuel from the vaporizing chamber, and means for admitting air to mix with said vaporized fuel.

2. In a vaporizer and carburetor, the combination with a float chamber and a vaporizing chamber, said chambers communicating with each other, a heating element associated with the vaporizing chamber, and means whereby the said vaporizing chamber may be vented when the pressure therein exceeds a predetermined limit.

3. In a vaporizer and carburetor, the combination with a float chamber, a vaporizing chamber communicating therewith, a heating element associated with said vaporizing chamber, a valve controlling the passage of the vaporized fuel from said vaporizing

chamber, an air intake, a valve for regulating the admission of air, a throttle valve, and means connecting all of said valves whereby they are dependently operated.

5. In a vaporizer and carbureter, the combination with a float chamber, a vaporizing chamber communicating therewith, a valve controlling the passage of vaporized fuel from said vaporizing chamber, an air inlet 10 a valve controlling said air inlet, and means operatively connecting the said valves whereby they are dependently operated.

6. In a vaporizer and carbureter, the combination with a casing containing a chamber 15 to which fluid fuel is supplied, a vaporizing chamber adjacent the fuel chamber and adapted to communicate therewith, a heating element adapted to be supported adjacent a wall of the said vaporizing chamber, 20 a valve controlling the passage of vaporized fuel from said vaporizing chamber, and an air inlet whereby the vaporized fuel and air may be mixed.

7. In a vaporizer and carbureter, the combination with a chamber adapted to contain a fuel supply, a vaporizing chamber communicating with the first mentioned chamber, a vent passageway associated with the vaporizing chamber, a removably supported valve 30 normally closing said passageway, whereby the vaporizing chamber may vent itself when the pressure therein exceeds a predetermined limit.

8. In a vaporizer and carbureter, the combination with a float chamber, a float in said chamber, a fuel inlet pipe to said chamber, a valve controlling the passage of fuel through 35 said pipe, operative connections between the valve and float, of a vaporizing chamber

communicating with the float chamber, a 40 heating element associated with the vaporizing chamber, excessive pressure within the vaporizing chamber serving to raise the level of liquid in the float chamber, thereby operating the float and shutting off the supply of fuel.

9. In a vaporizer and carbureter, the combination with a float chamber, of a vaporizing chamber communicating therewith, a valve controlling the passage of vaporized 50 fuel from said vaporizing chamber, a throttle valve, and means connecting said valves whereby they are dependently operated.

10. In a vaporizer and carbureter, the combination with a float chamber, of a vaporizing chamber communicating therewith, a valve controlling the passage of vaporized fuel from said chamber, a throttle valve, means connecting said valves whereby they are dependently operated, and a valve controlling the admission of air.

11. In a vaporizer and carbureter, the combination with a float chamber, of a vaporizing chamber communicating therewith, a valve controlling the passage of vaporized fuel from said vaporizing chamber, a valve for regulating the admission of air, a throttle valve, means connecting said valves whereby they are dependently operated, and an auxiliary automatic valve for admitting air.

In testimony whereof, I hereunto affix my signature in the presence of two witnesses.

PHELPS M. FREER.
